LIQUID FUEL BURNER

Aeneas MacDonald, Evanston, Ill.

Application July 20, 1936, Serial No. 91,480

5 Claims. (CL. 158—77)

The invention relates to improvements in liquid fuel burners and more particularly to the type employing a substantially horizontally disposed rotary atomizing cup having a novelly constructed primary air nozzle arranged to discharge into a fire box a thoroughly atomized liquid fuel spray in a manner to effect thorough combustion of all hydro-carbons in suspension.

Liquid fuel burners of the general type illustrated herein commonly include rotating means to discharge, under pressure, oil or other fuel into a fire box in a substantially straight tubular stream of fuel completely enclosed in a tubular wall of air discharged under pressure in the same direction as the liquid fuel. Such an arrangement prevents rather than assists thorough mixing of the air with the fuel prior to said stream being broken up by striking the refractory back wall of the fire box or a baffle, with the result that localized temperatures are in evidence. This manner of attempted atomization and burning of liquid fuel is highly objectional because much of the heat that is generated is lost, the refractory material is burned out and also due to the incomplete atomization of the liquid fuel, an excessive amount of carbon accumulates within the fire box to further minimize the effective heating.

With the ordinary type of burner there also is no known means provided to insure mixing of secondary air entering the fire box through the grates, with the result that a wall of cool air insulates the fire box walls and other parts from the heat of the flame.

It is therefore an object of the invention to provide the combination of a novelly constructed liquid fuel burner and a novel fire box structure to prevent cold air from entering the fire box and insulating the walls and other parts thereof against the heat within the box.

Another object is to provide means to insure complete combustion of the hydro-carbons in full suspension, thus minimizing operation and fuel costs and rendering unnecessary the frequent repairs to the refractory now occasioned with known types of burners.

Another object is to provide a liquid fuel burner of the type having a rotating fuel atomizing cup, with a novelly constructed nozzle for effecting a very intimate mixture of air and hydro-carbon.

Another object is to provide the fire box with a secondary air inlet suitably arranged with respect to the liquid fuel and primary air inlet to insure complete mixing of air and hydro-car-

bons and effect a perfect chemical and mechanical union of all combustible elements present.

Another object is to provide a nozzle for a liquid fuel burner with means to direct a stream of primary air angularly into the liquid fuel stream to effectively mix said fuel and air, and direct the atomized fuel in any angular direction relative to the axis of the burner.

Another object is to provide a fire box for liquid fuel with an inclined grate having a plurality of secondary air passages therein arranged to insure an adequate supply of fresh air to the flame at points required to insure perfect combustion.

Another object is to provide a liquid fuel burner with mechanical and low pressure air means to effect atomization of liquid fuel, including an atomizing cup and controlled means for controlling the angle of firing.

Another object is to provide a liquid fuel burner with means to control the direction of fire in all directions, upwardly, downwardly or sidewise.

Another object is to provide means to produce a substantially flat flame within the fire box and direct it in such a direction as to insure complete combustion of all fuel supplied thereto without impinging said fuel against the fire box walls or baffles therein.

Another object is to provide a liquid fuel burner with means to effect angle firing to produce a flame that will burn in suspension and have for its guidance a bed or strata of secondary air which forms a cushion between the floor and grate of the fire box and the flame, and thereby effect complete mixing of air and hydro-carbons to insure perfect fuel combustion with little or no loss of heat and no excess of cool air.

The foregoing and such other objects of the invention as will become apparent hereinafter as the description proceeds, will be more readily understood from a perusal of the following specification, reference being had to the accompanying drawing, in which:

Fig. 1 is a fragmentary vertical sectional view through the fire box of a heating plant, showing partly in elevation, a liquid fuel burner associated therewith embodying features of the invention.

Fig. 2 is an enlarged fragmentary longitudinal sectional view through the discharge end of the liquid fuel burner shown in Fig. 1.

Fig. 3 is a perspective of one form of improved nozzle.

Fig. 4 is a vertical sectional view through a nozzle embodying modified features of construction.

Fig. 5 is a front end elevational view of another form of nozzle.

Referring particularly to Figs. 1 to 3, inclusive, the liquid fuel burner, indicated generally at 11, preferably is mounted in a tilted position over the fire door opening 12 in one wall 13 of a fire box 14, with its nozzle 15 extending through the opening 12 substantially as shown. A flanged collar 16 preferably is carried on the rear end 10 of the nozzle 15 so that, if advisable, the opening 12, around said nozzle, can be tightly sealed. However, it is desirable that the collar 16 have suitable openings therein which may be closed by a rotatable ring 20 mounted on the collar. 15 The ring 20 has aligned openings so that, when in open position, air can enter the fire door opening around the nozzle 15 to prevent overheating of said nozzle.

The fire box 14 may be of any conventional 20 size or shape adapted for use with liquid fuel burners and preferably has an inclined grate 17 provided with a plurality of air passageways 18. The passageways 18 preferably are arranged horizontally in checker board fashion with the 25 maximum number of passages at the lower end, all of which may be wholly or partially closed by a suitable closure 19 preferably mounted over the front wall of the fire box whereby the volume of air admitted through the grate may be controlled.

The liquid fuel burner 11 may be of any conventional type embodying a casing 21 having an air ejector 22 therein operated by any suitable means such as, for example, motor 23. The 30 motor shaft 24, upon which the air ejector 22 is mounted, extends into the forward end of the casing 21 and has an atomizing cup 25 fixedly secured on its end, which, as best shown in Fig. 2, is axially positioned within a sleeve 26 extending inwardly from the discharge opening of the nozzle 15. Liquid fuel is supplied to the rear end portion 27 of the atomizing cup through a suitable conduit 28 and is entrained by the air stream created by ejector 22, through ports 29 into forward end portion 31 of said cup from where it is radially ejected into the fire box substantially in the manner indicated by the broken lines.

In known types of liquid fuel burners, having 50 conventional types of nozzles thereon, the liquid fuel is discharged from the rotating atomizing cup in a substantially straight stream horizontally into the fire box and a circular wall of primary air, passing out of the annular clearance 55 between the rotating cup 25 and the nozzle opening, surrounds said stream and effectively prevents complete atomization and mixing of the primary air with the hydro-carbons in the fuel.

To avoid this inefficient atomization and unsatisfactory partial combustion of the fuel, the improved nozzle 15 has at least one enlargement providing an auxiliary primary air passageway 32 preferably disposed above the fuel stream. As shown, the passageway 32 communicates with the interior of the nozzle and air flowing through said nozzle is broken up by the sleeve 26 so that some of said air flows through the annular opening between the atomizer and the sleeve 26 and the remainder flows through 65 passageway 32. Air discharged from said passageway 32, angularly downwardly, as shown, knocks down the upper half of the radially ejected fuel stream to produce a down-shot flame wherein the primary air and fuel are broken up and 70 thoroughly mixed. The agitation and knocking

down of the fuel directs the flame downwardly angularly substantially parallel to the plane of the inclined grate 17, as shown in Fig. 1. The flame however does not strike the refractory of the grate 17 or the floor due to a cushioning 5 layer of secondary air flowing over the grate through passageways 18.

Obviously much of this incoming secondary air striking the fuel stream substantially at right angles is projected directly into said stream, 10 thus increasing the atomization of the fuel to permit complete combustion. The arrangement shown also insures the introduction of a larger amount of secondary air at the upper portion of the grate because of the shorter air passageways 18. Inasmuch as the flame does not strike any of the refractory material lining of the fire box, said material is not destroyed nor is its efficiency impaired in any manner by the accumulation of carbon thereon. It is obvious also 20 that the nozzle 15 may be turned into any desired position for directing the flame angularly upwardly, downwardly or to either side thereby adapting the nozzle for use on burners installed in various types of fire boxes.

The modified form of nozzle 15^a, shown in Fig. 4, is similar to that previously described except that this nozzle has two auxiliary primary air passageways 32^a, one of which for the purpose of illustration is shown closed by a suitable cap 33. 30 The other primary air passageway has a curved sleeve extension 34 mounted on its end for adjustment whereby the point of intersection of the air ejected therefrom and the fuel stream may be varied to suit various types of installations. 35 The auxiliary air passageways 32^a each may be closed by a suitable butterfly valve 35 in lieu of the cap 33. It is apparent that three or even four auxiliary primary air passageways can be provided on the nozzle and that one or more 40 of said passageways may be fitted with adjustable extensions 34 and the remaining passageways closed either by a cap 33 or a butterfly valve 35. Use of this form of nozzle readily adapts a liquid fuel burner for use in any known 45 type of combustion chamber wherein it may be necessary to direct the flame angularly upwardly, downwardly, or sidewise or at any angle between the horizontal and vertical by opening the proper air passageway or passageways.

The nozzle shown in Fig. 5 differs from the previously discussed forms in that the outlet opening of the auxiliary air passageway 32^b preferably is crescent shaped to discharge a heavy stream of primary air onto the top side 55 of the fuel stream and a relatively light stream against the sides of said stream. This form of opening is more effective to knock down the sides of the fuel stream which, because of the rotation of the atomizer, might not be encountered by an air stream discharged from a nozzle of the type shown in Figs. 2 and 3.

The arrangements provided herein are such that a down-shot completely atomized highly volatile fuel mixture is delivered into the fire 65 box for complete consumption of all the hydro-carbon therein without the necessity of directing the fuel blast, as formerly, against the refractory or baffles which resulted in damage to said refractory or baffles, inefficient localized 70 heating and high cost operation.

Although exemplary embodiments of the improved nozzle and fire box have been illustrated in the accompanying drawing and described in detail in the foregoing specification, it is to be 75

clearly understood that the invention is capable of embodying various modifications in structural detail and that the improved burner nozzle is readily applicable to any known type of fire box and most conventional types of burners whether they use a rotary atomizer or not, and it is, therefore, not desired to limit the invention to the precise structures illustrated but to embody such modifications as fall within the spirit of the invention and the scope of the appended claims.

I claim:

1. In combination with a furnace having a fire box comprising an inclined grate provided with air admission openings, a liquid fuel burner including a blower and a rotary fuel atomizer for delivering an atomized fuel stream over said grate and into said fire box for ignition, and a nozzle on said burner including at least one angularly disposed air outlet for delivering an air stream angularly against the fuel stream to deflect said fuel stream toward said inclined grate.
2. In combination with a furnace having a fire box, an inclined grate in said fire box having a plurality of air passageways extending therethrough, a liquid fuel burner including a blower and a rotatable fuel atomizer for discharging an atomized fuel stream into said fire box, and adjustable means on said burner adapted to direct an air stream angularly against said fuel stream to deflect said fuel stream toward said grate.
3. In a furnace for burning liquid fuel, the combination of, a fire box including a front wall and a grate, a liquid fuel burner including a rotary fuel atomizer mounted in the front wall,

a nozzle on said burner for delivering a stream of air and fuel into said fire box above said grate, a spout on said nozzle having an air passageway for directing air downwardly angularly against the upper side of the stream to deflect said stream toward said grate, and said grate having a plurality of openings to deliver air against the lower side of said deflected stream in progressively decreasing amounts as the fuel moves across the top of said grate.

4. In combination with a furnace having a fire box provided with an inclined grate in one wall thereof, a liquid fuel burner including a blower and a rotary fuel atomizer for delivering an atomized fuel stream into said fire box for ignition, a nozzle on said burner surrounding said atomizer, said nozzle having a restricted discharge end to permit passage of a tubular column of air around said atomizer, and a spout communicating with the interior of the nozzle, said spout having an air outlet of substantially the same width as the diameter of the discharge end of said nozzle directed angularly towards said discharge end.

5. A furnace including a fire box having a front wall provided with an opening, a liquid fuel burner arranged to discharge a fuel stream through said opening, a floor in said fire box inclined downwardly rearwardly from a point just below the opening in said front wall, and means on said burner to direct an air stream angularly against the fuel stream for deflecting said fuel stream towards the floor, said floor having a plurality of passageways therethrough of different lengths to admit atmospheric air into said fire box below said fuel stream.

AENEAS MACDONALD.
